 Chas. Pfizer & Co., Inc., New York, N.Y., a corpora-
 tion of Delaware

No Drawing. Filed June 29, 1960, Ser. No. 39,717
 5 Claims. (Cl. 260—556)

This invention relates to new and useful disulfonamides in the benzene series. More particularly, it is concerned with novel N-substituted p-benzenedisulfonamides, i.e., 4-sulfamylbenzenesulfonamides, as well as with the alkali metal salts thereof. There is also included within the purview of this invention various pharmaceutical compositions which have at least one of the herein described compounds as their essential active ingredient.

The compounds which are included within the scope of this invention are selected from the group consisting of disulfonamides corresponding to the following general structural formulae:

and

and the alkali metal salts thereof, wherein X is a member selected from the group consisting of hydrogen, chlorine, bromine, nitro, cyano, trifluoromethyl, lower alkylmercapto and lower alkylsulfonyl wherein in each instance the lower alkyl group has from one to four carbon atoms, alkoxy having from one to four carbons and alkyl having from one to three carbon atoms; R is a member selected from the group consisting of hydrogen, alkyl having from one to four carbon atoms, aminopropyl, aminobutyl, mercaptomethyl, S-methylmercaptoprotoethyl, carboxymethyl, carboxyethyl, hydroxymethyl, α -hydroxyethyl, benzyl, p-hydroxybenzyl, p-hydroxyphenyl, carboxamidomethyl, γ -carboxamidoaminopropyl, γ -guanidylpropyl, 4-imidazolmethyl and β -indolemethyl; R' is a member selected from the group consisting of hydrogen and methyl, said R' being methyl only when R is ethyl; R'' is a member selected from the group consisting of hydrogen, alkyl having from one to ten carbon atoms, amino, N-mono(lower)alkylamino, N,N-di(lower)alkylamine, hydrazino, N-mono(lower)alkylhydrazino and N,N-di(lower)alkylhydrazino, wherein in each instance the lower alkyl group has from one to four carbon atoms; and R''' is a member selected from the group consisting of N-monoalkyl having from one to ten carbon atoms, N-monohalo(lower)alkylamino, N-monoalkyl having from two to eight carbon atoms, N-monocyclopropylamino, N-monocyclobutylamino, N-monocyclopentylamino, N-monocyclohexylamino, N-mono-

2

cycloheptylamino, N-monobenzylamino, N-mono(β -phenylethyl)amino, N-mono(m-xylyl)amino, N-mono(p-chlorobenzenohydryl)amino, N-anilino, N-(m-trifluoromethyl-anilino), N-(p-toluidino), N-(p-anisidino), N-mono(α -naphthyl)amino, N-mono(β -naphthyl)amino, 1-pyrryl, 1-imidazoyl, 1-pyrrolidyl, 1-piperidyl, 1-piperazyl, 1-(4-methylpiperazyl), 4-morpholinyl, 4-thiamorpholinyl, N,N-dibenzylamino and N,N-di(lower)alkylamino wherein said lower alkyl group has from one to four carbon atoms.

10 In accordance with the present invention, the aforementioned benzenedisulfonamides all exhibit interesting pharmacological properties which render them useful as synthetic medicinals. For instance, the compounds of this invention are extremely valuable as carbonic anhydrase inhibitors, i.e., they inhibit the activity of carbonic anhydrase and this, in turn, serves to depress the central nervous system and increase the amount of water and sodium excreted in the urine. Hence, these compounds are particularly useful for suppressing excitability 15 in animals and for protecting them against convulsive seizures or for combatting same. In addition, they can also be employed in the treatment of edema and like conditions in view of the diuretic properties which they possess, especially those compounds of the amino acid substituted 20 type. Among the many typical examples of compounds included within the purview of the present invention are N-monoisopropyl-p-benzenedisulfonamide, N-monoallyl-p-benzenedisulfonamide, N-monocyclohexyl-p-benzenedisulfonamide, N-monobenzyl-p-benzenedisulfonamide, N-(m-trifluoromethylphenyl)-p-benzenedisulfonamide, N-(α -naphthyl)-p-benzenedisulfonamide, N-(4-sulfamylbenzenesulfonyl)glycine, N-(4-sulfamylbenzenesulfonyl)alanine, N-(4-sulfamylbenzenesulfonyl)glycine ethyl ester, N-(4-sulfamylbenzenesulfonyl)glycine amide, N-(4-sulfamylbenzenesulfonyl)glycine N-(n-propyl)amide, N-(4-sulfamylbenzenesulfonyl)glycine hydrazide, N-(2-chloro-4-sulfamylbenzenesulfonyl)glycine, N-(2-trifluoromethyl-4-sulfamylbenzenesulfonyl)alanine, N-(3-nitro-4-sulfamylbenzenesulfonyl)lysine, N-(4-sulfamylbenzenesulfonyl)-glutamic acid, N-(3-chloro-4-sulfamylbenzenesulfonyl)-histidine, N-(4-sulfamylbenzenesulfonyl)tryptophane, and the like.

In accordance with the process for preparing the compounds of this invention, an appropriate 4-sulfamylbenzenesulfonyl chloride is treated with a primary organic amine of the formula R'''NH₂ or with an α -amino acid type compound of the formula H₂NCRR'COOR'' wherein R, R', R'', and R''' are all as previously defined. This reaction can best be carried out in accordance with the general method of O. Hinsberg et al. as originally reported in the *Chemische Berichte*, vol. 23, p. 2962 (1890), and *ibid.*, vol. 38, p. 906 (1905), although in the case of the basic diaminoacids it is necessary that the second or non- α -amino group be first protected via conventional 45 blocking techniques, e.g., by a carbobenzyloxy group. In the latter connection, it is preferable to first form a copper chelate salt of the desired diamino acid and then treat the latter intermediate with benzyl chloroformate, followed by removal of the copper with hydrogen sulfide. After 50 completion of the disulfonamide-formation step, the carbobenzyloxy blocking group is removed via hydrogenolysis 55 in accordance with standard procedures well known to those skilled in the art.

The sulfamylbenzenesulfonyl chloride starting materials employed in this process are readily prepared from

the corresponding sulfanilamide compounds via the general procedure of H. Meerwin et al. as described in the *Chemische Berichte*, vol. 90, p. 841 (1957). In the present instance, this method involves first diazotizing the amino group of one of the aforementioned sulfanilamides and then treating the resulting diazonium salt so obtained with sulfur dioxide in a glacial acetic acid solvent medium containing cupric chloride at a temperature that is in the neighborhood of 5° C., i.e., within the range of from about -5° C. to about 10° C.

The alkali metal salts of the compounds of this invention are easily obtained in accordance with conventional methods. In general, such methods involve dissolving the selected 4-sulfamylbenzenesulfonamide in an aqueous or alcoholic solution of an alkali metal hydroxide, such as sodium hydroxide, potassium hydroxide, lithium hydroxide, and the like, and concentrating the resulting solution so obtained.

As previously indicated, the compounds of the present invention are readily adapted to therapeutic use as diuretic agents and/or as anti-convulsants. Furthermore, the toxicity of these particular N-substituted p-benzenedisulfonamides has been found to be quite low when they are administered to mice in amounts that are sufficient to achieve the desired therapeutic effects. Moreover, no other harmful pharmacological side effects have been observed to occur as a result of their administration.

In accordance with a method of treatment of the present invention, the herein described benzenedisulfonamide derivatives can be administered to an agitated subject via the oral or parenteral routes. In general, these compounds are most desirably administered in doses ranging from about 200 mg. to about 2000 mg. per day, although variations will necessarily occur depending upon the weight of the subject being treated and the particular route of administration chosen. However, a dosage level that is in the range of from about 2.8 mg. to about 28.0 mg. per kg. of body weight per day is most desirably employed in order to achieve effective results. Nevertheless, it is to be appreciated that still other variations may also occur in this respect, depending upon the severity of the patient's condition and its individual response to said medicament, as well as on the particular type of formulation chosen and the time period and interval at which such administration is carried out. In some instances, dosage levels below the lower limit of the aforesaid range may be more than adequate, while in other cases still larger dosages may be employed without causing any harmful or deleterious side effects provided that such higher levels are first divided into several smaller doses that are to be administered throughout the day.

In connection with the use of the benzenedisulfonamide compounds of this invention for the treatment of an epileptic subject, it is to be noted that they may be administered either alone or in combination with a pharmaceutically acceptable carrier by either of the routes previously indicated, and that such administration can be carried out in both single and multiple dosages. More particularly, the novel compounds of this invention can be administered in a wide variety of dosage forms, i.e., they may be combined with various pharmaceutically acceptable inert carriers in the form of tablets, capsules, lozenges, troches, hard candies, powders, aqueous suspensions, injectable solutions, elixirs, syrups, and the like. Such carriers include solid diluents or fillers, sterile aqueous media and various non-toxic organic solvents, etc. Moreover, such oral pharmaceutical compositions can be sweetened and/or flavored by means of various agents of the type commonly employed for such a purpose. In general, the therapeutically-active compounds of this invention are present in such dosage forms at concentration levels ranging from about 0.5% to about 90% by weight of the total composition, i.e., in amounts which are suffi-

cient to provide the desired unit dosage previously indicated.

For purposes of oral administration, tablets containing various excipients such as sodium citrate, calcium carbonate and dicalcium phosphate may be employed along with various disintegrants such as starch and preferably potato or tapioca starch, alginic acid and certain complex silicates, together with binding agents such as polyvinyl-pyrrolidone, sucrose, gelatin and acacia. Additionally, lubricating agents such as magnesium stearate, sodium lauryl sulfate and talc are often very useful for tabletting purposes. Solid compositions of a similar type may also be employed as fillers in soft elastic and hardshelled gelatin capsules; preferred materials in this connection would also include lactose or milk sugar, as well as high molecular weight polyethylene glycols. When aqueous suspensions and/or elixirs are desired for oral administration, the essential active ingredient may be combined with various sweetening or flavoring agents, coloring matter or dyes and, if so desired, emulsifying and/or suspending agents, together with such diluents as water, ethanol, propylene glycol and glycerin, as well as various like combinations thereof.

For purposes of parenteral administration, solutions of the benzenedisulfonamides in sesame or peanut oil or in aqueous-propylene glycol may be employed, as well as sterile aqueous solutions of the corresponding water-soluble alkali metal salts previously enumerated. Such aqueous solutions should be suitably buffered if necessary and the liquid diluent rendered isotonic with sufficient glucose or saline. These particular solutions are especially suitable for intravenous, intramuscular and subcutaneous injection purposes. Needless to say, the necessary steps should be taken throughout the preparation of these injectable solutions so as to ensure that final products are obtained in a sterile condition.

This invention is further illustrated by the following examples, which are not to be construed as imposing any limitations on the scope thereof. On the contrary, it is to be clearly understood that resort may be had to various other embodiments, modifications and equivalents thereof which readily suggest themselves to those skilled in the art without departing from the spirit of the present invention and/or the scope of the appended claims.

Example I

To 200 ml. of chlorosulfonic acid there is added 50 g. of dry o-chloroacetanilide with constant agitation being maintained throughout the addition. After the foaming subsides, the reaction mixture is heated to 100° C. and maintained at that point for two hours. Upon removal of the excess chlorosulfonic acid via evaporation under reduced pressure, there is obtained a residual material which is subsequently treated with ice water. The precipitated product is then recovered by means of filtration, washed with water and air dried to constant weight.

To the 3-chloro-4-acetamidobenzenesulfonyl chloride prepared as described in the above manner, there is added a slight excess of concentrated ammonium hydroxide diluted with an equal amount of water. The resultant solution is slowly-heated with occasional stirring and maintained just below the boiling point for about five minutes. The pasty suspension which forms is cooled in an ice bath, filtered and the filter cake so collected is pressed dry on the funnel with the aid of suction. Upon recrystallization of the product from acetonediethyl ether, there is obtained pure 3-chloro-4-acetamidobenzenesulfonamide. Hydrolysis of the latter compound with dilute hydrochloric acid in accordance with standard organic procedure affords 3-chloro-4-aminobenzenesulfonamide.

Example II

The procedures described in Example I are followed except that m-chloroacetanilide is the starting material employed. In this case, the latter compound is suc-

sively converted to 2-chloro-4-acetamidobenzenesulfonyl chloride, 2-chloro - 4 - acetamidobenzenesulfonamide and 2-chloro - 4 - aminobenzenesulfonamide, respectively. In like manner, o-trifluoromethylacetanilide and m-trifluoromethylacetanilide are readily converted via this same series of reactions to 3-trifluoromethyl-4-aminobenzenesulfonamide and 2-trifluoromethyl-4-aminobenzenesulfonamide, respectively. Inasmuch as the various number of products which can be prepared in accordance with the two-step series of reactions employed in this example form a large but yet determinable number of compounds, the following list of acetanilide starting materials is presented below in order to avoid unnecessary repetition. In each and every case, the corresponding sulfanilamide compound is the final product obtained.

o-Bromoacetanilide
o-Methylacetanilide
m-Nitroacetanilide
o-Cyanoacetanilide
m-Methylmercaptoacetanilide
m-Methylsulfonylacetanilide
o-Methoxyacetanilide
m-Methylacetanilide
m-Cyanoacetanilide
o-Nitroacetanilide
m-Bromoacetanilide
o-Ethylmercaptoacetanilide
m-Ethylsulfonylacetanilide
o-Ethoxyacetanilide
o-Ethylacetanilide
o-(n-Propylmercapto)ethylacetanilide
m-(n-Propylsulfonyl)ethylacetanilide
m-Isopropoxyacetanilide
o-(n-Propyl)acetanilide
m-(n-Butylmercapto)acetanilide
o-(n-Butylsulfonyl)acetanilide
o-(n-Butoxy)acetanilide

Example III

In a 500 ml. three-necked, round-bottomed flask equipped with a mechanical stirrer, thermometer and dropping funnel, there is placed 76.8 g. (0.372 mole) of 3 - chloro - 4 - aminobenzenesulfonamide and 125 ml. of water. Stirring is initiated and 63 ml. (0.744 mole) of concentrated hydrochloric acid is rapidly added to the agitated slurry. After cooling the resulting solution to below 0° C. by means of an aqueous acetone Dry-Ice bath, a saturated aqueous solution containing 26.5 g. (0.372 mole, 97% purity) of sodium nitrite is added via the dropping funnel at such a rate that the temperature of the solution does not rise above 0° C.

The above diazonium solution is then rapidly added with stirring to 350 ml. of a saturated solution of sulfur dioxide in glacial acetic acid (20-25% by weight) to which a saturated aqueous solution containing 50 g. of cupric chloride dihydrate had already been added. Upon completion of this step, the ice-bath is removed and the reaction mixture is stirred for about ten minutes at room temperature. The precipitated product is then collected by means of filtration and washed well with cold water. In this manner, there is obtained pure crystalline 2-chloro-4-sulfamylbenzenesulfonyl chloride.

Example IV

When 2-chloro-4-aminobenzenesulfonamide is the starting material employed in the reaction procedure of the foregoing example, the corresponding product obtained is 3 - chloro - 4 - sulfamylbenzenesulfonyl chloride. In like manner, 3-trifluoromethyl-4-aminobenzenesulfonamide is converted to 2-trifluoromethyl - 4 - aminobenzenesulfonyl chloride; 2-trifluoromethyl-4-aminobenzenesulfonamide is converted to 3-trifluoromethyl-4-sulfamylbenzenesulfonyl chloride; and 4-aminobenzenesulfonamide is converted to 4-sulfamylbenzenesulfonyl chloride.

Inasmuch as the total number of products which can

be prepared in accordance with this example form a large but yet determinable number of compounds, the following list of sulfonamide starting materials is presented below in order to avoid unnecessary repetition of experimental detail. In each and every case, the corresponding 4-sulfamylbenzenesulfonyl chloride is the product obtained.

3-bromo-4-aminobenzenesulfonamide
2-nitro-4-aminobenzenesulfonamide
3-cyano-4-aminobenzenesulfonamide
2-methylmercapto-4-aminobenzenesulfonamide
2-methylsulfonyl-4-aminobenzenesulfonamide
3-methoxy-4-aminobenzenesulfonamide
2-methyl-4-aminobenzenesulfonamide
2-cyano-4-aminobenzenesulfonamide
3-nitro-4-aminobenzenesulfonamide
2-bromo-4-aminobenzenesulfonamide
3-ethylmercapto-4-aminobenzenesulfonamide
2-ethylsulfonyl-4-aminobenzenesulfonamide
3-ethoxy-4-aminobenzenesulfonamide
3-ethyl-4-aminobenzenesulfonamide
3-(n-propyl)mercapto-4-aminobenzenesulfonamide
2-(n-propylsulfonyl)-4-aminobenzenesulfonamide
2-isopropoxy-4-aminobenzenesulfonamide
3-(n-propyl)-4-aminobenzenesulfonamide
2-(n-butylercapto)-4-aminobenzenesulfonamide
3-(n-butyrsulfonyl)-4-aminobenzenesulfonamide
3-(n-butoxy)-4-aminobenzenesulfonamide

30

Example V

To 3 g. (0.039 mole) of glycine contained in a 200 ml. round-bottomed flask equipped with mechanical stirrer, thermometer and reflux condenser there is added 80 ml. of a 1N sodium hydroxide solution. Stirring is commenced and when complete solution is effected there is then added 10 g. (0.039 mole) of 4-sulfamylbenzenesulfonyl chloride in small portions during the course of a fifteen minute period. Vigorous agitation is then maintained for an additional hour with the necessary precautions being taken to maintain the temperature of the reaction mixture in the 15-20° C. range. The reaction solution is also tested from time to time throughout this period to be certain that it is still basic to litmus paper. Upon completion of this step, the reaction mixture is cooled and filtered, and the resulting filtrate acidified with concentrated hydrochloric acid. After allowing said solution to stand overnight in an icebox, crystallization of the desired product slowly occurs (this process can be hastened by scratching the walls of the glass container with a stirring rod). The crystalline product is then collected by means of filtration, washed with water and air dried to afford an 81% yield of N-4-sulfamylbenzenesulfonyl-glycine, M.P. 234-235° C.

Analysis.—Calcd. for $C_8H_{11}N_2O_6S_2$: C, 32.65; H, 3.42; N, 9.52. Found: C, 32.61; H, 3.55; N, 9.63.

Example VI

The procedure described in Example V is followed except for the fact that the amino acid employed is alanine instead of glycine. Thus, when equimolar amounts of 4-sulfamylbenzenesulfonyl chloride and alanine react in accordance with this procedure, there is obtained a 28% yield of N-(4-sulfamylbenzenesulfonyl)alanine, M.P. 195-196° C.

Analysis.—Calcd. for $C_9H_{12}N_2O_6S_2$: C, 35.06; H, 3.92; N, 9.09. Found: C, 34.75; H, 3.87; N, 9.05.

Example VII

The procedure described in Example V is followed except that derivatives of glycine are individually employed as starting materials in lieu of the parent acid itself. Thus, when equimolar amounts of 4-sulfamylbenzenesulfonyl chloride and glycine ethyl ester react in accordance with this procedure, there is obtained a 52% yield of

N-(4-sulfamylbenzenesulfonyl)glycine ethyl ester, M.P. 184-185° C.

Analysis.—Calcd. for $C_{10}H_{14}N_2O_6S_2$: C, 37.26; H, 4.38; N, 8.69. Found: C, 37.12; H, 4.45; N, 8.65.

In like manner, equimolar amounts of 4-sulfamylbenzenesulfonyl chloride and glycine amide react to afford a 78% yield of N-(4-sulfamylbenzenesulfonyl)glycine amide, M.P. 242-243° C.

Analysis.—Calcd. for $C_8H_{11}N_3O_5S_2$: C, 32.76; H, 3.78; N, 14.33. Found: C, 32.51; H, 3.90; N, 14.54.

Similarly, equimolar amounts of 4-sulfamylbenzenesulfonyl chloride and glycine hydrazide react to afford a 69% yield of N-(4-sulfamylbenzenesulfonyl)glycine hydrazide, M.P. 191-192° C.

Analysis.—Calcd. for $C_8H_{12}N_4O_5S_2$: C, 31.16; H, 3.92; N, 19.17. Found: C, 30.72; H, 4.10; N, 18.29.

In the same manner, equimolar amount of 4-sulfamylbenzenesulfonyl chloride and glycine N-(n-propyl)amide react to afford a 95% yield of N-(4-sulfamylbenzenesulfonyl)glycine N-(n-propyl)amide, M.P. 145-146° C.

Analysis.—Calcd. for $C_{11}H_{17}N_3O_5S_2$: C, 39.39; H, 5.11; N, 12.53. Found: C, 39.20; H, 5.37; N, 12.51.

Example VIII

The procedure described in Example V is followed except that 2-chloro-4-sulfamylbenzenesulfonyl chloride is the starting material employed. Thus, when equimolar amounts of this particular sulfonyl chloride and glycine react in accordance with the reaction conditions of this procedure, the corresponding product obtained is N-(2-chloro-4-sulfamylbenzenesulfonyl)glycine. In like manner and employing equimolar amounts of starting material and reagent in each case, 3-chloro-4-sulfamylbenzenesulfonyl chloride and alanine react to afford N-(3-chloro-4-sulfamylbenzenesulfonyl)alanine; 2-trifluoromethyl-4-sulfamylbenzenesulfonyl chloride and alanine react to afford N-(2-trifluoromethyl-4-sulfamylbenzenesulfonyl)alanine; 3-trifluoromethyl-4-sulfamylbenzenesulfonyl chloride and aline react to afford N-(3-trifluoromethyl-4-sulfamylbenzenesulfonyl)aline; 4-sulfamylbenzenesulfonyl chloride and aline react to afford N-(4-sulfamylbenzenesulfonyl)aline; 2-bromo-4-sulfamylbenzenesulfonyl chloride and norvaline react to afford N-(2-bromo-4-sulfamylbenzenesulfonyl)norvaline; 3-nitro-4-sulfamylbenzenesulfonyl chloride and norvaline react to afford N-(3-nitro-4-sulfamylbenzenesulfonyl)norvaline; 2-cyano-4-sulfamylbenzenesulfonyl chloride and leucine react to afford N-(2-cyano-4-sulfamylbenzenesulfonyl)leucine; 3-methylmercapto-4-sulfamylbenzenesulfonyl chloride and leucine react to afford N-(3-methylmercapto-4-sulfamylbenzenesulfonyl)leucine; 3-methylsulfonyl-4-sulfamylbenzenesulfonyl chloride and norleucine react to afford N-(3-methyl-4-sulfamylbenzenesulfonyl)norleucine; 2-methoxy-4-sulfamylbenzenesulfonyl chloride and norleucine react to afford N-(2-methoxy-4-sulfamylbenzenesulfonyl)norleucine; 3-methyl-4-sulfamylbenzenesulfonyl chloride and isoleucine react to afford N-(3-methyl-4-sulfamylbenzenesulfonyl)isoleucine; 2-trifluoromethyl-4-sulfamylbenzenesulfonyl chloride and isoleucine react to afford N-(2-trifluoromethyl-4-sulfamylbenzenesulfonyl)isoleucine; 3-cyano-4-sulfamylbenzenesulfonyl chloride and isovaline react to afford N-(3-cyano-4-sulfamylbenzenesulfonyl)isovaline; 2-nitro-4-sulfamylbenzenesulfonyl chloride and isovaline react to afford N-(2-nitro-4-sulfamylbenzenesulfonyl)isovaline; 2-chloro-4-sulfamylbenzenesulfonyl chloride and phenylalanine react to afford N-(2-chloro-4-sulfamylbenzenesulfonyl)phenylalanine; 3-bromo-4-sulfamylbenzenesulfonyl chloride and phenylalanine react to afford N-(3-bromo-4-sulfamylbenzenesulfonyl)phenylalanine; 2-ethylmercapto-4-sulfamylbenzenesulfonyl chloride and tyrosine react to afford N-(2-ethylmercapto-4-sulfamylbenzenesulfonyl)tyrosine; 3-ethylsulfonyl-4-sulfamylbenzenesulfonyl chloride and tyrosine

react to afford N-(3-ethylsulfonyl-4-sulfamylbenzenesulfonyl)tyrosine; 2-ethoxy-4-sulfamylbenzenesulfonyl chloride and serine react to afford N-(2-ethoxy-4-sulfamylbenzenesulfonyl)serine; 2-ethyl-4-sulfamylbenzenesulfonyl chloride and serine react to afford N-(2-ethyl-4-sulfamylbenzenesulfonyl)serine; 3-bromo-4-sulfamylbenzenesulfonyl chloride and α -amino- β -hydroxybutyric acid react to afford α -[N-(3-bromo-4-sulfamylbenzenesulfonyl)amino]- β -hydroxybutyric acid; 2-cyano-4-sulfamylbenzenesulfonyl chloride and α -amino- β -hydroxybutyric acid react to afford α -[N-(2-cyano-4-sulfamylbenzenesulfonyl)amino]- β -hydroxybutyric acid; 3-nitro-4-sulfamylbenzenesulfonyl chloride and cysteine react to afford N-(3-nitro-4-sulfamylbenzenesulfonyl)cysteine; 4-sulfamylbenzenesulfonyl chloride and cysteine react to afford N-(4-sulfamylbenzenesulfonyl)cysteine; 2-(n-propylmercapto)-4-sulfamylbenzenesulfonyl chloride and methionine react to afford N-[2-(n-propylmercapto)-4-sulfamylbenzenesulfonyl]methionine; 3-(n-propylsulfonyl)-4-sulfamylbenzenesulfonyl chloride and methionine react to afford N-[3-(n-propylsulfonyl)-4-sulfamylbenzenesulfonyl]methionine; 2-trifluoromethyl-4-sulfamylbenzenesulfonyl chloride and aspartic acid react to afford N-(2-trifluoromethyl-4-sulfamylbenzenesulfonyl)aspartic acid; 3-isopropoxy-4-sulfamylbenzenesulfonyl chloride and aspartic acid react to afford N-(3-isopropoxy-4-sulfamylbenzenesulfonyl)aspartic acid; 2-(n-propyl)-4-sulfamylbenzenesulfonyl chloride and glutamic acid react to afford N-[2-(n-propyl)-4-sulfamylbenzenesulfonyl]glutamic acid; 4-sulfamylbenzenesulfonyl chloride and glutamic acid react to afford N-(4-sulfamylbenzenesulfonyl)glutamic acid; 3-chloro-4-sulfamylbenzenesulfonyl chloride and arginine react via the corresponding δ -guanidyl carbobenzyloxy derivative of said diamino acid to afford N-(3-chloro-4-sulfamylbenzenesulfonyl)arginine; 2-bromo-4-sulfamylbenzenesulfonyl chloride and arginine react via the corresponding δ -guanidyl carbobenzyloxy derivative of said diamino acid to afford N-(2-bromo-4-sulfamylbenzenesulfonyl)arginine; 3-nitro-4-sulfamylbenzenesulfonyl chloride and lysine react via the corresponding ϵ -amino-carbobenzyloxy of said diamino acid to afford N-(3-nitro-4-sulfamylbenzenesulfonyl)lysine; 4-sulfamylbenzenesulfonyl chloride and lysine react via the corresponding ϵ -amino-carbobenzyloxy derivative of said diamino acid to afford N-(4-sulfamylbenzenesulfonyl)lysine; 2-cyano-4-sulfamylbenzenesulfonyl chloride and ornithine react via the corresponding δ -aminocarbobenzyloxy derivative of said diamino acid to afford N-(2-cyano-4-sulfamylbenzenesulfonyl)ornithine; 3-(n-butylmercapto)-4-sulfamylbenzenesulfonyl and ornithine react via the corresponding δ -aminocarbobenzyloxy derivative of said diamino acid to afford N-[3-(n-butylmercapto)-4-sulfamylbenzenesulfonyl]ornithine; 2-(n-butylsulfonyl)-4-sulfamylbenzenesulfonyl chloride and asparagine react to afford N-[2-(n-butylsulfonyl)-4-sulfamylbenzenesulfonyl]asparagine; 3-trifluoromethyl-4-sulfamylbenzenesulfonyl chloride and asparagine react to afford N-(3-trifluoromethyl-4-sulfamylbenzenesulfonyl)asparagine; 2-(n-butoxy)-4-sulfamylbenzenesulfonyl chloride and citrulline react to afford N-[2-(n-butoxy)-4-sulfamylbenzenesulfonyl]citrulline; 2-methyl-4-sulfamylbenzenesulfonyl chloride and citrulline react to afford N-(2-methyl-4-sulfamylbenzenesulfonyl)citrulline; 3-chloro-4-sulfamylbenzenesulfonyl chloride and histidine react to afford N-(3-chloro-4-sulfamylbenzenesulfonyl)histidine; 2-bromo-4-sulfamylbenzenesulfonyl chloride and histidine react to afford N-(2-bromo-4-sulfamylbenzenesulfonyl)histidine; 3-nitro-4-sulfamylbenzenesulfonyl chloride and tryptophane react to afford N-(3-nitro-4-sulfamylbenzenesulfonyl)tryptophane; and 4-sulfamylbenzenesulfonyl chloride and tryptophane react to afford N-(4-sulfamylbenzenesulfonyl)tryptophane.

Example IX

The procedure described in Example V is followed except that other starting materials of the type employed in Example VII are individually used. Inasmuch as the other amino acids employed in Example VIII also form these same type derivatives, the products prepared in this particular example form a large but determinable number of compounds. Accordingly, the following list of ester, amide and hydrazide derivatives of alanine is hereinafter presented in order to avoid unnecessary repetition of experimental details, although it is to be understood that similar type derivatives of the other α -amino acids listed as starting materials in Example VIII are equally applicable in the present instance. The ester derivatives of alanine so employed include the following lower alkyl esters thereof: methyl, ethyl, isopropyl, n-butyl, isoamyl, n-hexyl, 2-ethylhexyl, n-octyl and n-decyl. The amide derivatives of alanine so employed include the parent glycine amide as well as the following N-monoalkyl and N,N-dialkyl derivatives thereof: N-methylcarboxamide, N,N-dimethylcarboxamide, N-ethylcarboxamide, N-isopropylcarboxamide, and N,N-di(n-butyl)carboxamide. The hydrazide derivatives of alanine so employed include alanine hydrazide itself as well as the following N-monoalkyl and N,N-dialkyl derivatives thereof: N,N-dimethylcarbohydrazide, N-ethylcarbohydrazide, N-isopropylcarbohydrazide, and N,N-di(n-butyl)carbohydrazide.

Example X

To 2.3 g. (0.039 mole) of isopropylamine contained in a 200 ml. round-bottomed flask equipped with mechanical stirrer, thermometer and reflux condenser there is added 30 ml. of a 10% aqueous sodium hydroxide solution. Stirring is commenced and when complete solution is effected there is then added 10 g. (0.039 mole) of 4-sulfamylbenzenesulfonyl chloride in small portions during the course of fifteen minute period. The remainder of the procedure, including the isolation step, is essentially the same as that described in Example IV. In this manner, there is obtained a 71% yield of N-monoisopropyl-p-benzenedisulfonamide, M.P. 167-168° C.

Analysis.—Calcd. for $C_9H_{14}N_2O_4S_2$: C, 38.83; H, 5.07; N, 10.07. Found: C, 38.73; H, 4.99; N, 10.13.

Example XI

The procedure described in Example X is followed except for the fact that allylamine is the starting material employed in place of the isopropylamine used in the previous example. Thus, when equimolar amounts of 4-sulfamylbenzenesulfonyl chloride and allylamine react in accordance with this procedure, there is obtained a 69% yield of N-monoallyl-p-benzenedisulfonamide, M.P. 154-155° C.

Analysis.—Calcd. for $C_9H_{12}N_2O_4S_2$: C, 39.11; H, 4.38; N, 10.14. Found: C, 39.01; H, 4.45; N, 9.89.

Example XII

The procedure described in Example X is followed except that cyclohexylamine is the starting material employed in lieu of isopropylamine. Thus, when equimolar amounts of 4-sulfamylbenzenesulfonyl chloride and cyclohexylamine react in accordance with this procedure, there is obtained a 60% yield of N-monocyclohexyl-p-benzene-disulfonamide, M.P. 202-203° C.

Analysis.—Calcd. for $C_{12}H_{18}N_2O_4S_2$: C, 45.26; H, 5.70; N, 8.80. Found: C, 44.92; H, 5.66; N, 9.20.

Example XIII

The procedure described in Example X is followed except that benzylamine is the starting material employed in lieu of isopropylamine. Thus, when equimolar amounts of 4-sulfamylbenzenesulfonyl chloride and benzylamine react in accordance with this procedure, there is obtained a 60% yield of N-monobenzyl-p-benzenedisulfonamide, M.P. 196-197° C.

Analysis.—Calcd. for $C_{13}H_{14}N_2O_4S_2$: C, 47.84; H, 4.32; N, 8.58. Found: C, 47.90; H, 4.14; N, 8.49.

Example XIV

The procedure described in Example X is followed except that m-trifluoromethylaniline is the starting material employed in lieu of isopropylamine. Thus, when equimolar amounts of 4-sulfamylbenzenesulfonyl chloride and m-trifluoromethylaniline react in accordance with this procedure, there is obtained a 52% yield of N-(m-trifluoromethylphenyl)-p-benzenedisulfonamide, M.P. 167-168° C.

Analysis.—Calcd. for $C_{13}H_{11}F_3N_2O_4S_2$: C, 41.05; H, 2.92; N, 7.37. Found: C, 40.71; H, 2.77; N, 7.66.

Example XV

The procedure described in Example X is followed except that α -naphthylamine is the starting material employed in lieu of isopropylamine. Thus, when equimolar amounts of 4-sulfamylbenzenesulfonyl chloride and α -naphthylamine react in accordance with this procedure, there is obtained a 33% yield of N-mono(α -naphthyl)-p-benzenedisulfonamide, M.P. 241-242° C.

Analysis.—Calcd. for $C_{16}H_{14}N_2O_4S_2$: C, 53.02; H, 3.89; N, 7.73. Found: C, 52.98; H, 4.03; N, 7.95.

Example XVI

The procedure described in Example X is followed except that methylamine (40% in water) is the starting material employed in lieu of isopropylamine. Thus, when equimolar amounts of 4-sulfamylbenzenesulfonyl chloride and methylamine react in accordance with this procedure, there is obtained a 61% yield of N-monomethyl-p-benzenedisulfonamide, M.P. 158-159° C.

Analysis.—Calcd. for $C_7H_{10}N_2O_4S_2$: C, 33.59; H, 5.03; N, 11.19. Found: C, 33.85; H, 4.13; N, 11.40.

Example XVII

The procedure described in Example X is followed except that β -bromoethylamine is the starting material employed in lieu of isopropylamine. Thus, when equimolar amounts of 4-sulfamylbenzenesulfonyl chloride and β -bromoethylamine react in accordance with this procedure, there is obtained a 63% yield of N-mono(β -bromoethyl)-p-benzenedisulfonamide, M.P. 154-155° C.

Analysis.—Calcd. for $C_8H_{11}BrN_2O_4S_2$: C, 28.00; H, 3.23; N, 8.16. Found: C, 27.99; H, 3.22; N, 8.31.

Example XVIII

The procedure described in Example X is followed except that piperidine is the starting material employed in lieu of isopropylamine. Thus, when equimolar amounts of 4-sulfamylbenzenesulfonyl chloride and piperidine react in accordance with this procedure there is obtained a 48% yield of N-piperidyl-p-benzenedisulfonamide, M.P. 220-221° C.

Analysis.—Calcd. for $C_{11}H_{16}N_2O_4S_2$: C, 43.40; H, 5.30; N, 9.21. Found: C, 43.43; H, 5.26; N, 9.16.

Example XIX

The procedure described in Example X is followed except that dibenzylamine is the starting material employed in lieu of isopropylamine. Thus, when equimolar amounts of 4-sulfamylbenzenesulfonyl chloride and dibenzylamine react in accordance with this procedure, there is obtained a 27% yield of N,N-dibenzyl-p-benzene-disulfonamide, M.P. 178-179° C.

Analysis.—Calcd. for $C_{20}H_{20}N_2O_4S_2$: C, 57.67; H, 4.84; N, 6.73. Found: C, 57.54; H, 4.89; N, 6.80.

Example XX

The procedure described in Example X is essentially followed except that other amine starting materials of the type used in Examples X-XIX are individually employed in the present instance in lieu of isopropylamine. Inasmuch as the products prepared in this example form

a large but yet determinable number of compounds, the following list of amine starting materials is presented below in order to avoid unnecessary repetition of experimental details. In each and every case, the corresponding N-substituted p-benzenedisulfonamide is the final product obtained:

Ethylamine (33% in water)	β -Phenylethylamine
n-Propylamine	m-Xylylamine
Isobutylamine	p-Chlorobenzohydrylamine
n-Butylamine	Aniline
Isoamylamine	p-Toluidine
n-Amylamine	p-Anisidine
n-Hexylamine	β -Naphthylamine
n-(2-ethyl)hexylamine	Pyrrole
n-Decylamine	Imidazole
δ -Chlorobutylamine	Piperazine
γ -Iodopropylamine	Pyrrolidine
Vinylamine	4-Methylpiperazine
β -Methallylamine	Morpholine
2-octenylamine-1	Thiomorpholine
Cyclopropylamine	Dimethylamine (25% in water)
Cyclopentylamine	Diethylamine
Cyclobutylamine	Di-isopropylamine
Cycloheptylamine	Di-(n-butyl)amine

Example XXI

The procedure described in Example X is followed except that the 4-sulfamylbenzenesulfonyl chloride starting materials used in Example VIII are also individually employed in the present instance for just such purposes in lieu of 4-sulfamylbenzenesulfonyl chloride. Such sulfonyl chloride starting materials specifically include 2-chloro-4-sulfamylbenzenesulfonyl chloride, 3-chloro-4-sulfamylbenzenesulfonyl chloride, 2-trifluoro-4-sulfamylbenzenesulfonyl chloride and 3-trifluoromethyl-4-sulfamylbenzenesulfonyl chloride. In each case, the corresponding ring substituted N-monoisopropyl-p-benzene-disulfonamide is the product obtained.

Example XXII

N-(4-sulfamylbenzenesulfonyl)glycine is dissolved in an aqueous solution containing an equivalent amount of sodium hydroxide. Upon concentration of the resultant solution under reduced pressure, there is obtained the monosodium salt of N-(4-sulfamylbenzenesulfonyl)glycine. In the same manner, the corresponding potassium and lithium salts are prepared by merely employing the appropriate alkali metal hydroxide solution in each case. In like manner, each of the other N-monosubstituted disulfonamide products reported in the previous examples react with anyone of the foregoing hydroxides to afford the corresponding alkali metal salts. In all of these cases, the salts so formed are especially suitable for the preparation of injectable aqueous solutions as previously indicated in the specification.

Example XXIII

A dry solid pharmaceutical composition is prepared by blending the following materials in the proportions by weight specified:

N-monobenzyl-p-benzenedisulfonamide	10
Potato starch	20
Dicalcium phosphate	45
Lactose	15

Polyvinylpyrrolidone	8
Magnesium stearate	2

After the dried composition is thoroughly blended, tablets are punched from the resulting mixture, each tablet being of such size that it contains 100 mg. of the active ingredient.

Example XXIV

A dry solid pharmaceutical composition is prepared by combining the following materials in the proportions by weight specified:

N-monoisopropyl-p-benzenedisulfonamide	10
Polyethylene glycol (average molecular weight, 6000)	30
Lactose	40
Calcium carbonate	20

The dried solid mixture so prepared is thoroughly agitated so as to obtain a powdered product that is completely uniform. Soft elastic and hard-shelled gelatin capsules containing this pharmaceutical composition are then prepared employing a sufficient quantity of material so as to furnish 250 mg. of the active ingredient in each capsule.

Example XXV

An aqueous propylene glycol solution containing the monosodium salt of N-(4-sulfamylbenzenesulfonyl) glycine is prepared by dissolving the latter compound in propylene glycol-water (1:3 by weight) with the aid of gentle heating. The amount of compound employed is such that the resulting solution contains 5 mg. of the active ingredient per ml. After cooling to room temperature, it is sterilized by means of filtration through a Seitz filter. The sterile aqueous propylene glycol solution so obtained is suitable for intramuscular administration to animals.

What is claimed is:

1. N-monoallyl-p-benzenedisulfonamide.
2. N-monocyclohexyl-p-benzenedisulfonamide.
3. N-monobenzyl-p-benzenedisulfonamide.
4. N-mono (m-trifluoromethylphenyl) - p - benzenedisulfonamide.
5. N-mono(α -naphthyl)-p-benzenedisulfonamide.
